UNITED STATES PATENT OFFICE

164,310

DRIPLESS PITCHER

Maurice R. Mechem, Clarion, Iowa

Application March 5, 1951, Serial No. 14,386

Term of patent 14 years

(Cl. D44—21)

To all whom it may concern:

Be it known that I, Maurice R. Mechem, a citizen of the United States, residing at Clarion, in the county of Wright, and State of Iowa, have invented a new, original, and ornamental Design for a Dripless Pitcher, of which the following is a specification, reference being had to the accompanying drawing, forming a part thereof.

Fig. 1 is a perspective view of a dripless pitcher showing my new design;

Fig. 2 is a side elevational view; and

Fig. 3 is a top plan view thereof.

I claim:

The ornamental design for a dripless pitcher, substantially as shown.

MAURICE R. MECHEM.
